UNITED STATES PATENT OFFICE

EDWARD J. BRENNAN, OF HASBROUCK HEIGHTS, NEW JERSEY

DESIGN FOR A CONTAINER CAP

Application filed July 14, 1932. Serial No. 44,325. Term of patent 14 years.

To all whom it may concern:

Be it known that I, EDWARD J. BRENNAN, a citizen of the United States, residing at 127 Raymond Street, Hasbrouck Heights, Bergen County, State of New Jersey, have invented a new, original, and ornamental Design for a Container Cap, of which the following is a specification, reference being had to the accompanying drawing, forming a part thereof.

I claim:

The ornamental design for a container cap, as shown.

EDW. J. BRENNAN.
